UNITED STATES PATENT OFFICE.

PAUL M. PLACE, OF BRIDGEPORT, CONNECTICUT.

RADIATOR HANGER.

Application filed June 27, 1922. Serial No. 571,288.

To all whom it may concern:

Be it known that I, PAUL M. PLACE, a citizen of the United States, residing at Bridgeport, county of Fairfield, State of Connecticut, have invented an Improvement in Radiator Hangers, of which the following is a specification.

This invention relates to a hanger especially for supporting a radiator on a vertical wall. It is an object of the invention to provide an improved hanger of this type which comprises few and simple parts and so will be comparatively cheap to manufacture and not liable to get out of order.

It is also an object of the invention to provide an improved hanger which may be easily applied to walls already built and which when once applied will be very secure and hold considerable weight without pulling out.

It is a further object of the invention to provide a hanger which will be inconspicuous and practically invisible after the radiator is suspended therefrom and also one which will provide sufficient adjustment that it will accommodate practically all the standard radiators now generally in use.

With the foregoing and other objects in view I have devised the construction illustrated in the accompanying drawing, in which—

Fig. 1 is a front elevation of a radiator supported on my improved hanger.

Fig. 2 is a transverse section thereof immediately forward of the hanger showing the method of securing the same to a wall.

Fig. 3 is a view similar to Fig. 1 showing a different type of radiator.

Fig. 4 is a transverse section substantially on the line 4—4 of Fig. 3.

Fig. 5 is a similar view of a slightly modified construction adapted for attachment to a wooden frame construction.

Fig. 6 is a front view of the construction shown in Fig. 5.

Fig. 7 is a plan view of the upper plate.

Fig. 8 is a plan view of the radiator support.

Fig. 9 is an edge view of the plate shown in Fig. 7, and

Fig. 10 is an elevation of the suspending bolt.

Referring particularly to Figs. 1 and 2, the numeral 10 indicates a standard type of radiator adapted to be suspended from a wall. My hanger comprises a flat metal plate

11 having an upturned flange 12 at one end and an elongated transversely extending slot 13 adjacent the other end. This plate is adapted to be inserted in the joints between two adjacent horizontal rows of bricks. The plate may be built into the wall when the bricks are laid as shown in Fig. 2, in which case the upper brick 14 is preferably laid directly on the plate with the flange 12 extending into the joint back of this brick, and the end of the plate provided with an elongated slot projecting outwardly from the face of the wall.

If the plate is to be attached to a wall already built the mortar between two adjacent rows of bricks, as shown at 15 in Fig. 4, is dug out to a sufficient depth for insertion of the flange on the plate to the extent desired. In this form of mounting, when the weight of the radiator is applied to the projecting end of the plate, the flange 12 is forced into or against the brick or mortar as the case may be and hold the plate very securely in position. It will be evident that when the weight of the radiator is applied to the plate it will be practically impossible to dislodge the same.

The radiator support comprises a metal plate 16 shaped substantially as shown in Figs. 2, 5, and 8 with a recess 17 preferably V-shaped in its upper edge to form a seat for the connecting flanges or unions 18 between the radiator sections. It is also preferred to form a recess 19 in this plate rearwardly of the seat for the radiator so that this seat may be raised with respect to the plate 11 when the support is suspended therefrom but this recess may be omitted if desired. The plate or support 16 is also provided with an opening 20 to the rear thereof and below the recess 17 to receive a bolt 21. This bolt is preferably provided with a hook 22 at its lower end adapted to extend through the opening 20 and is threaded at its upper end at 23 to receive a nut 24. It will be apparent that by inserting the hook through the opening 20 and also inserting the threaded end of the bolt through elongated slot 13 after the plate 11 has been placed in position, and applying the nut 24, the radiator support 16 will be suspended from the plate 11 with its inner upright edge 25 against the surface of the wall. The radiator may now be placed with the connection between the sections seated in the recess 17 and will be securely mounted on the wall.

By making the recess 17 V-shaped it may be easily made of sufficient depth that the rod 26 usually employed between the radiator sections will not be required to sustain any of the weight of the radiator.

The distance at which the slot 13 is located outwardly from the face of the wall is determined when the plate 11 is secured in position, and because of the slot 13 it will be evident that the support 16 may be given considerable adjustment transversely of the plate 11, the amount of this adjustment of course depending upon the length of the slot. The dimensions are preferably made such that the support 16 may be always located midway between two adjacent sections of the radiator. It will be apparent the height of the support 16 may be easily adjusted by means of the nut 24. In mounting the suspending bolt in position I preferably place a washer 27 between the nut and the top of the plate 11.

In the form shown in Figs. 5 and 6 I have formed the suspending plate 28 corresponding to the plate 11 in Figs. 1 and 2 so that it may be secured to a wooden frame construction. This plate is bent at substantially right angles intermediate its ends with the upright portion 29 provided with suitable openings for securing means, such as bolts or screws 30, adapted to attach the same to the upright woodwork 31, the horizontal portion 32 of the plate 28 which projects outwardly from the face of the wall being provided with the transverse slot 13 to receive the bolt 21 as in the first form.

It will be apparent from the foregoing that in the form shown in Figs. 2 and 4 the greater the weight of the radiator the more securely will the plate 11 and the flange thereon engage the brick work and be secured in position therein. It will also be apparent that all the adjustments required are provided, that the whole hanger comprises very few parts which are very simple in construction and may be easily set up and adjusted, and when the radiator is suspended therefrom it is practically invisible.

Having thus described the nature of my invention, what I claim is:

1. A radiator hanger comprising a plate adapted to be secured to a wall and project horizontally therefrom, said plate being provided with a slot extending transversely thereof outside the wall, a radiator support comprising an upright plate having a recess at its upper end to receive a radiator and an opening extending transversely therethrough rearwardly of said recess, a hooked bolt extending through said opening

and said slot in the first mentioned plate, and a nut on said bolt above said plate.

2. A radiator hanger comprising a plate adapted to be inserted between two adjacent horizontal rows of bricks in a wall, said plate having an upturned flange on its inner end to engage the brick and a free end adapted to project horizontally from the face of the wall, and a radiator support suspended from the projecting portion of said plate, the rear edge of the second mentioned plate being adapted when in supporting position to engage the vertical surface of the wall and being free and unrestricted against lateral movement.

3. A radiator hanger comprising a flat plate adapted to be inserted between two adjacent horizontal rows of brick in a wall, said plate having an upturned flange on its inner end to engage the brick and a free end adapted to project horizontally from the face of the wall and having a transversely extending elongated slot therein, a radiator support comprising a plate having a seat for a radiator, and a bolt secured to said plate and extending through said slot.

4. A radiator hanger comprising a plate having an upturned flange at its inner end and adapted to be inserted between two adjacent horizontal rows of bricks with the other end projecting from the face of the wall and provided with a transverse slot, a radiator support comprising an upright plate having a seat for a radiator in its upper edge and provided with an opening, a hooked bolt extending through said opening and slot whereby the plate is suspended with an upright edge against the face of the wall, and a nut on the bolt above the first mentioned plate.

5. A radiator hanger comprising a plate having an upturned flange at its inner end and adapted to be inserted between two adjacent horizontal rows of bricks with the other end projecting from the face of the wall and provided with a transverse slot, a radiator support comprising an upright plate having a seat for a radiator in its upper edge and provided with an opening, a hooked bolt extending through said opening and slot whereby the upright plate is suspended with an upright rear edge against the face of the wall, said rear edge of the upright plate being free and unobstructed against lateral movement, and a nut on the bolt above the first mentioned plate.

In testimony whereof I affix my signature.

PAUL M. PLACE.
